DESIGN FOR A CASE FOR AN OCTANT OR THE LIKE

Harold A. Marsh, Binghamton, N. Y., assignor to
Link Aviation Devices, Inc., Binghamton, N. Y.

Application October 3, 1941, Serial No. 103,629

Term of patent 14 years

To all whom it may concern:

Be it known that I, Harold A. Marsh, a subject of England, residing at Binghamton, in the county of Broome and State of New York, have invented a new, original, and ornamental Design for a Case for an Octant or the like, of which the following is a specification, reference being had to the accompanying drawing, forming part thereof.

Fig. 1 is a side perspective view of a case for an octant or the like, showing my new design;

Fig. 2 is a side elevational view;
Fig. 3 is an elevational view of one end; and
Fig. 4 is an elevational view of the other end of the design.

I claim:

The ornamental design for a case for an octant or the like, as shown.

HAROLD A. MARSH.
